[57] CLAIM

The ornamental design for a motorcycle caliper cover, as shown and described.

DESCRIPTION

FIG. 1 is a left side elevational view of a motorcycle caliper cover embodying my new design in position of use shown in reduced scale, the right side elevational view being substantially a mirror image thereof, it being understood that the broken lines are for illustration purposes only;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof.
